UNITED STATES PATENT OFFICE.

DEROY RILEY, OF COVENTRYVILLE, NEW YORK.

SHINGLE-SAWING MACHINE.

SPECIFICATION forming part of Letters Patent No. 355,473, dated January 4, 1887.

Application filed April 5, 1886. Serial No. 197,910. (No model.)

To all whom it may concern:

Be it known that I, DEROY RILEY, a citizen of the United States, residing at Coventryville, in the county of Chenango and State of New York, have invented certain new and useful Improvements in Shingle - Machines; and I do hereby declare that the following is a full, clear, and exact description of the same, reference being had to the annexed drawings, making a part of this specification, and to the letters and figures of reference marked thereon.

Figure 1 of the drawings is a perspective view of my invention; Fig. 2, a top plan view thereof with a portion of the frame partly broken away. Fig. 3 is a vertical section taken on line $x-x$ of Fig. 2; Fig. 4, a detail view in perspective of the tilting frame, supporting-bracket, cam-block, and toothed wheel; and Fig. 5 a detail view showing the relative position of the several belt-pulleys.

The present invention has for its object to provide a simple, effective, and easily-operated machine for sawing shingles; and it consists in the several details of construction, substantially as shown in the drawings, and hereinafter described and claimed.

The dogs B are pressed out against the inner ends of the blocks by a coiled or other suitable spring, d, inclosed within a casing, e, also connected to the sides of the arms b, said casing also forming a guide for the rear end of the dog, into which it enters.

The carriage A is connected to the upper end of a vertical shaft, g, which has its bearing in the cross-beams h i of the frame of the machine. The under side of the carriage has centrally connected to it a large cog-wheel, C, with which engages a pinion, k, upon the end of a vertical shaft, l. The shaft l has keyed to it a belt-pulley, D, and is connected with a cone-pulley, E, by means of an endless belt passing around said pulleys, a second endless belt in like manner connecting the cone-pulley E with a similar cone-pulley, F. These cone-pulleys are of the usual construction and employed in the ordinary manner for changing the speed of a main pulley, and in the present instance they are used for the purpose of regulating the speed of the carriage by shifting the belt on said cone-pulleys, thus adapting the machine for different work. In

order to regulate and vary the speed of the several parts, the driving force is primarily imparted to the cone-pulley E.

The saw G is connected to one end of a shaft, m, which has its bearings in the frame of the machine, and is provided with a pulley, H, around which passes the driving-belt. This pulley H is connected with the cone-pulley F by an endless belt, and by means of these endless-belt connections and pulleys motion is given to the shaft l, and through the medium of the pinion k and toothed wheel C a rotary motion is imparted to the carriage.

The upper side of the carriage A is provided with a circular support, I, for the blocks from which the shingles are cut, in order to have them within convenient reach of the attendant to feed them to the machine, the support also forming a brace for the carriage at its axial center to strengthen it.

After the block is taken from the support I it is placed on a tilting table, K, of any suitable construction, but preferably in the form of a skeleton-frame, as shown in Fig. 4, said table being retained in a horizontal position by a spring, n.

The table K is pivoted to a suitable bracket, L, provided with a rod, o, screw-threaded at its lower end, and extends down through an elongated slot, p, in the cross-piece q of the frame of the machine. The two arms r of the bracket L extend up through holes in a cross-piece, s, of the frame, and by means of the jam-nuts on the screw-threaded end of the rod o the bracket can be raised or lowered to increase or diminish its height with relation to the carriage, and is held in its adjusted position by the jam-nuts above described. This adjustment of the bracket L is to change the position of the tilting table K, which is pivoted to the arms r of said bracket, thereby regulating the thickness or taper of the shingle and style of head, the table at all times being below the top of the frame of the machine, so that the block, when taken up by the dogs B from off the table, will be brought against the saw in such relation thereto as to cut therefrom the desired thickness of shingle. The cross-pieces q s, if preferred, may be hinged to one of the standards M of the frame of the machine, or in any other well-known manner connected

thereto, so as to admit of the cross-pieces swinging in or out by means of the crank screw-rod S, thereby enabling the bracket, with its tilting table, to be shifted to cut any style of head desired on the shingle. The rod S is connected at one end to the cross-piece q, and the screw-threaded portion thereof engages with a screw-threaded hole in one of the standards M, which is located opposite the free end of the cross-piece q. These two cross-pieces are connected together by a suitable brace, u, forming a frame to which is attached, as hereinbefore described, the bracket L.

The bracket L has a bifurcated arm, N, to form bearings for the shaft of a block, O, the shaft thereof having connected to its inner end a toothed wheel, P. The block O acts as a cam to raise the inner end of the tilting frame K, and has flat sides in number to correspond with the number of teeth on the wheel P. In the present instance I have shown four teeth, which are operated upon by pins v, depending from the under side of the carriage A, and come successively in contact with the teeth as the carriage revolves, thus turning the block and bringing the cam-faces thereof against the under side of the table, which will tilt it.

Although the block O has flat sides, the corners of the block act in the capacity of cams to raise the table as they are brought against it, and therefore I shall hereinafter term the device a "cam-block."

The cam-block P, as will be noticed, is tapering, and held on the shaft a' by a set-screw, b', to enable said block to have its ends reversed, or to adjust it longitudinally on the shaft. The object of reversing the block or adjusting it on the shaft is to bring a different diameter of the block in contact with the under side of the tilting table when the shaft a' is turned, thereby regulating the extent to which the table will tilt, and consequently regulating the thickness and taper of the shingle.

The table, as should be understood, is for the purpose of bringing the block from which the shingles are cut into position previous to coming in contact with the saw, so that each time the block is acted upon by the saw a shingle will be cut therefrom of uniform size and thickness.

The tripping device f on the under side of the dog B, which is provided with a friction-roller, w, is acted upon by a cam-track, R, as the carriage revolves, said track being connected to the top of the frame of the machine, and extends about one-fourth around the same.

The cam-track at its forward end gradually approaches nearer the axis of the carriage, so that the action of the track upon the dog will draw it from the block to release it before the block reaches the table, thus enabling the block to get in position on the table for a shingle to be cut therefrom, or to be removed from the machine.

The saw G is guarded by an extension, T,

to the frame of the machine, which, if preferred, may be provided with a trough or any other suitable device for carrying off the dust from the saw, as in the usual manner.

A chute, U, is employed to receive the cut shingles from the saw and deposit them in a receptacle placed under the chute, or deposit them in a pile on the floor, as found desirable.

In the operation of the machine the blocks from which the shingles are to be cut are held to the frame A by the dogs B, as hereinbefore stated. As the carriage revolves in the direction of the arrows the tripping device f, with its roller w, is brought successively in frictional contact with the inner face of the cam-track R, which will gradually draw in the dog and release it from the block, leaving the block free to adjust itself on the table K, after which it is again taken up by the dog in its adjusted position and carried against the saw G. The shingle having been cut from the block, the latter is carried over the saw and around until it is released by the cam-track R, acting on the tripping device f, to force in the dog, as above described, after which the block will be free to again adjust itself on the table K, so that a second shingle can be cut therefrom, the dog again holding the block to the carriage in this adjusted position by the action of the spring d immediately on release of the dog by the cam-track, or when the dog has passed beyond the forward end of the track.

Immediately upon release of the block by the dog the table K is brought to the desired incline by the pins v coming in contact with one of the teeth of the wheel P, which turns the shaft a', and brings one corner of the cam-block O against the under side of the table, and in so doing raises that end, and thereby the shingle-block when received on the table will be supported at the desired incline to cut therefrom a shingle of the required taper when taken up by the dog and brought against the saw.

I do not wish to be understood as confining myself to any particular arrangement of belts and pulleys for imparting to the saw and carriage the desired motion, as any well-known means may be substituted for this purpose that will successfully attain the end desired, and any suitable construction of frame may be used for supporting the several parts of the machine; and I reserve the right, therefore, to make any such changes in my invention that come within ordinary mechanical skill, and use any material—such as wood or metal—from which to construct the several parts of the machine.

Having now fully described my invention, what I claim as new, and desire to secure by Letters Patent, is—

1. The combination, with a supporting frame and a vertical shaft and horizontal saw thereon, of a bracket, L, having its lower end bearing adjustably in said frame and provided with arms r r, a tilting table mounted on said arms, a bifurcated arm extending integrally

from said bracket, a tilting device mounted in said arm, a circular revolving table for actuating said tilting device, spring-dogs carried by said table, and a cam-track, R, adapted to 5 operate said dogs to drop the blocks on the tilting table and again seize them for presentation to the saw, substantially as set forth.

2. In a shingle-machine, the combination, with a horizontally-rotating carriage provided 10 with means for holding the shingle-blocks thereto and releasing them, of a tilting table to receive the blocks, and means for intermittently tilting said table, consisting of a shaft

provided with a tapering cam-block adjustable thereon, and a toothed wheel operated 15 upon by pins depending from the under side of the carriage, substantially as and for the purpose described.

In testimony that I claim the above I have hereunto subscribed my name in the presence 20 of two witnesses.

DEROY RILEY.
